Alfred L. Simpson Inventor
By his Attorney, Ruth F. Schucht

UNITED STATES PATENT OFFICE.

ALFRED L. SIMPSON, OF NEW YORK, N. Y., ASSIGNOR TO IDA L. SIMPSON, OF NEW YORK, N. Y.

SCREEN FOR PROJECTING APPARATUS.

No. 890,101.

Specification of Letters Patent.

Patented June 9, 1908.

Application filed August 15, 1907. Serial No. 388,742.

To all whom it may concern:

Be it known that I, ALFRED L. SIMPSON, a citizen of the United States, and a resident of New York, in the county of New York and State of New York, have invented certain new and useful Improvements in the Screen for Projecting Apparatus, of which the following is a specification.

My invention relates to the art of projecting images, and it has for its object a screen which will render possible the projecting of images thereon with sufficient brilliancy to be distinctly visible, although the said screen be exposed to diffused light of ordinary intensity.

My invention will be best understood in connection with the accompanying drawing which is a diagrammatic illustration of my invention.

20 In the projection of images, either stationary or moving, as at present carried out by the usual and well known apparatus, the screen upon which the images are projected is in the dark as well as the place in 25 which the observers are, in order that the said images may appear with sufficient brilliancy to enable said observers to clearly distinguish the same.

The object of my invention is to avoid the 30 darkening of the room or place in which the screen is placed, so that the lights forming the usual illumination as in a theater or hall may be left burning while the images are being projected. For this purpose I 35 project the images by means of projecting apparatus such as the lantern 10, or other well known forms of projecting apparatus, upon a specially prepared screen 11; and prefer also to somewhat increase the intensity 40 of the focused light. The screen consists of a base 11 provided with a surface 12 upon which the images are projected. Such a surface may be either smooth or bright, or relatively rough and dull. The screen is 45 best prepared by providing a suitable base 11 with a surface 12 preferably composed of minute metallic particles.

I prefer to employ powdered aluminum or aluminum bronze mixed with a suitable 50 vehicle such as amyl acetate or varnish, as a coating. The screen may, however, con-

sist simply of a metallic sheet such as a sheet of aluminum or metallic composition resembling the same. I may also form a composition for the surface by grinding tin 55 foil or other material colored with the three primary colors—red, yellow and blue forming thereby a composite surface which will bring out more perfectly the colors when projecting colored images. When an image 60 is projected upon a screen of this character it appears with perfect clearness, notwithstanding the usual illumination existing in the hall or the like in which the said image is being projected. This is due to the fact 65 that a screen of this character possesses the property of reflecting a relatively greater proportion of the focused rays than the usual screens employed.

By actual experiment in which two 70 screens were hung side by side in a room of the usual illumination (one screen being perfectly white and the other coated with a preparation of aluminum powder), it was found that when a picture was thrown 75 simultaneously from the same lantern so as to cover both, that the picture on the former screen was very unsatisfactory and indistinct, while the picture on the latter screen appeared perfectly snappy and brilliant. 80

I claim:

1. A screen for projected images consisting of a base of suitable material, and a metallic coating of the character specified.

2. A screen for projected images consisting of a base of suitable material, and a coating of metallic particles of the character specified. 85

3. A screen for projected images consisting of a base of suitable material, and a coating of powdered aluminum. 90

4. A screen for projected images consisting of a base of suitable material, and a colored, metallic coating of the character specified. 95

Signed at New York in the county of New York and State of New York.

ALFRED L. SIMPSON.
